UNITED STATES PATENT OFFICE.

EMIL KEMENY, OF NEW YORK, N. Y., ASSIGNOR TO OWEN WALSH M'FG. CO., INC., OF NEW YORK, N. Y., A CORPORATION OF NEW YORK.

DESIGN FOR A WALL LIGHTING FIXTURE.

Application filed April 13, 1926. Serial No. 17,281. Term of patent 3½ years.

To all whom it may concern:

Be it known that I, EMIL KEMENY, a citizen of Hungary, residing at New York city, county and State of New York, have invented a new, original, and ornamental Design for a Wall Lighting Fixture, of which the following is a specification, reference being had to the accompanying drawing, forming part thereof.

The figure is a perspective view of a wall lighting fixture showing my new design.

I claim as my invention:

The ornamental design for a wall lighting fixture substantially as shown.

EMIL KEMENY.
